(57) **CLAIM**

The ornamental design for a set of measuring spoons, as shown and described.

DESCRIPTION

FIG. 1 is an exploded, isometric view of a front, top, and right side of an ornamental design for a set of measuring spoons;

FIG. 2 is an exploded, front elevational view of the set of measuring spoons of FIG. 1;

FIG. 3 is an exploded, rear elevational view of the set of measuring spoons of FIG. 1;

FIG. 4 is an exploded, right side elevational view of the set of measuring spoons of FIG. 1;

FIG. 5 is an exploded, left side elevational view of the set of measuring spoons of FIG. 1;

FIG. 6 is an exploded, top plan view of the set of measuring spoons of FIG. 1;

FIG. 7 is an exploded, bottom plan view of the set of measuring spoons of FIG. 1;

FIG. 8 is an isometric view of a front, top, and right side of the set of measuring spoons shown in FIGS. 1-7 depicted in a nested configuration;

FIG. 9 is a front elevational view of the set of measuring spoons of FIG. 8;

FIG. 10 is a rear elevational view of the set of measuring spoons of FIG. 8;

FIG. 11 is a right side elevational view of the set of measuring spoons of FIG. 8;

FIG. 12 is a left side elevational view of the set of measuring spoons of FIG. 8;

FIG. 13 is a top plan view of the set of measuring spoons of FIG. 8; and,

FIG. 14 is a bottom plan view of the set of measuring spoons of FIG. 8.

The dash-dash-dash lines are included for the purpose of illustrating portions of the set of measuring spoons that form no part of the claimed design. The dash-dot-dash lines showing boundary lines form no part of the claimed design.

1 Claim, 8 Drawing Sheets
